atto. 33

UNITED STATES PATENT OFFICE.

BERT A. JOHNSON, OF MANDAN, NORTH DAKOTA.

SHOCK-LOADING MACHINE.

Application filed February 11, 1921. Serial No. 444,258.

To all whom it may concern:

Be it known that I, BERT A. JOHNSON, a citizen of the United States, residing at Mandan, in the county of Morton and State 5 of North Dakota, have invented certain new and useful Improvements in Shock-Loading Machines, of which the following is a specification.

This invention relates to agricultural machinery and the object is to provide a practical, efficient and comparatively simple shock loader of such design and construction that it will pick the grain shocks off the field and elevate them onto a wagon. The 15 invention is clearly illustrated in the accompanying drawings, in which;

Fig. 1 is a top or plan view of the machine, with various parts broken away.

Fig. 2 is an enlarged detail sectional view 20 of a time tip adapted to be used on the gathering prongs 8.

Fig. 3 is a detail sectional view on the line 3—3 in Fig. 1, looking in the direction of the arrow A.

Fig. 4 is a fragmentary top view of the 25 roller actuating mechanism.

Fig. 5 is a fragmentary sectional view on the line 5—5 in Fig. 1, looking in the direction of the arrow B.

Fig. 6 is a sectional view of the elevator 30 on the line 6—6 in Fig. 1, looking in the direction of the arrow C.

Fig. 7 is an enlarged detail sectional view 35 on the line 7—7 in Fig. 6, looking in the direction of the arrow D.

In the various views of the drawings like characters refer to like parts.

Referring to the drawings by reference numerals, 9 designates a frame which is supported mainly on the bull wheel 10 and the side wheel 11. Extending rearwardly from the machine is a heavy tongue 12 which is supported at its rear end on a steering wheel 13, and said wheel 13 is steered by a handle 14 actuated by the operator of the machine 40 who stands on the platform 15. Pivotaly mounted at 16 is an evener 17, to each end of which is secured double trees 18 to which are hitched the horses which propel the machine.

On the frame 9 is mounted a carrier frame 19 having horizontal side walls 20 and inclined side walls 21. The upper edge of the rear wall 20 is provided with a guard board

22 which prevents grain bundles from being 55 thrown rearwardly off the carrier.

In the horizontal portion of the carrier frame 19 is rotatably mounted two rollers 23 and 24, and a third roller 25 is mounted in the upper end of the inclined portion 21. An apron 26 having slats 27 is stretched over said rollers 23, 24 and 25. The ends 28 of each of these slats travel in grooves 29 in the side walls of the carrier frame. At intervals along the length of the apron 26 certain slats 27^a, thereon, are provided with inner oscillatable rods 30 having integral tines 31 which extend through slots 32 in the slats. The rods 30 are provided at their inner ends with integral fingers 33 which extend at right angles to the direction of the tines 31, (see Figs. 6 and 7). These fingers 33 do not come in contact with any of the rollers 23, 24, 25 as they pass between the ends of the rollers and the carrier frame 70 walls, (see Figs. 3, 4, 6 and 7), and they extend inwardly while on both runs of the horizontal carrier and while on the lower run of the inclined carrier. When they start on the upper run of the inclined carrier they 75 are pushed up into longitudinal relation with the apron 26 by the lower end of strips 34 which are secured to the inner sides of the carrier walls 21. This action raises the tines 31 to a perpendicular position, as 80 shown in Figs. 1, 6 and 7, where they are maintained by the strips 34 until the top of the inclined frame is reached. The tines are then thrown over until they come in contact with the top edge of a flat wall 35 which 85 brings and holds them up against the apron 26 while on its downward trip. A floor 36 on the horizontal portion of the frame serves a similar purpose as the wall 35 on the inclined portion. It may be noticed that a 90 space is left open between the adjacent ends of the wall 35 and floor 36 so that the straight tines 31 will not bind when passing over the roller 24. For the same reason the left end (see Fig. 6) of the floor 36 is terminated before reaching the roller 23.

The shafts 37 and 38 of the two rollers 23 and 24, are respectively provided with bevel pinions 39 and 40, which mesh respectively with bevel pinions 41 and 42 which are fixed 105 on a shaft 43, journaled in suitable bearings 44. One end of the shaft 43 is provided with a sprocket gear 45 which is connected

by a sprocket chain 46 to a sprocket pinion 47. The sprocket pinion 47 is fixed on a stud shaft 48 as is also a pinion 49 which meshes with an idler pinion 50, journaled on a stud shaft 51. The pinion 50 meshes with a gear 52 which is fixed on and rotated by the bull wheel 10.

The shocks of grain are picked up and thrown onto the horizontal carrier by a mechanism which is mounted in a frame 53. Mounted to oscillate in the rear part of this frame 53 is a shaft 54, which is provided with a plurality of forwardly extending integral gathering prongs 8, which rest with their middle parts on the offset portion 55 of a shaft 56. One end of the shaft 56 is provided with a lever arm 57 which is pivoted at 58 to a long rearwardly extending connecting rod 59. The rear end 20 of the rod 59 is pivoted at 60 to a foot lever 61, which in turn is pivoted at 62 to the tongue 12 near the platform 15. When the prongs 8 are in raised position, as shown, the center 60 is slightly lower than the center 62 so that the weight of the prongs will lock themselves into lifted position when the joint 60 is pressed down by the foot of the operator of the machine. When he desires to let the prongs 8 down into operating position he merely steps on the toe piece 63 of the lever 61 until the center 60 is raised above the pivot 62, when it will swing upward and backward allowing the prongs to come down.

A third shaft 64 is mounted in the frame 53 and on it are provided two series of oppositely directed and slightly curved picker prongs 65. On one end of the shaft 64 is a sprocket gear 66 which is connected by a sprocket chain 67 to a sprocket gear 68 fixed on and driven by the shaft 43.

In Fig. 2 is shown an improved construction of tine tip especially adapted for use on the gathering tines or prongs 8. The tine is provided with a knob 69 on its under side which rides on the ground, while in its end is inserted a pin 70 which is yieldingly held in extended position by a spring 71. Thus the tine is provided with a comparatively sharp point, but if such point should meet with any obstruction it will yield rearwardly into the tine which will then, by reason of the knob 69 pass thereover.

In the operation of the machine, when shocks are to be gathered, the gathering prongs 8 are lowered until they rest on the ground. The machine, to the double trees 18 of which are hitched the horses, is pushed over the ground. As the prongs 8 are pushed under a shock the picker tines 65 engage the bundles of grain and throw them back onto the horizontal carrier. As the apron 26 starts on its upward course in the inclined carrier frame, the tines 31 as they are brought to the perpendicular position,

as above described, prevent the bundles from rolling backward. As the bundles are carried to the top of the elevator they are thrown over into a wagon (not shown) which travels along with the machine.

It is understood that suitable modifications may be made in the form and structure of this invention if such modifications come within the spirit and scope of the appended claims. Having now therefore fully shown and described my invention what I claim to be new and desire to protect by Letters Patent is:

1. In a shock loader having a suitable wheel supported frame adapted to be propelled forwardly, a carrier frame positioned transversely on said frame, an endless conveyor mounted in the carrier frame, the upper part of said conveyor having a horizontal run and an inclined run leading upwardly therefrom, series of tines pivotally mounted to and arranged to swing axially from spaced transverse slats in said carrier, said tines normally resting rearwardly on the conveyor, means for automatically raising said tines to substantially perpendicular position while traveling up said inclined run of the conveyor, and means for holding said tines rearwardly up against the under side of the conveyor during the return run thereof.

2. In a shock loader, a suitable wheel supported frame adapted to be propelled forwardly, a carrier frame positioned transversely on said frame, an endless conveyor mounted in the carrier frame, the upper part of said conveyor having a horizontal run and an inclined run leading upwardly therefrom, series of tines pivotally mounted to spaced transverse slats in said carrier said tines normally resting rearwardly on the conveyor, means for automatically raising said tines to substantially perpendicular position while traveling up said inclined run of the conveyor, and a floor on the carrier frame for holding said tines rearwardly up against the underside of the conveyor during the return trip of the horizontal run thereof.

3. In a shock loader having a suitable wheel supported frame adapted to be propelled forwardly, a carrier frame positioned transversely on said frame, an endless conveyor mounted in the carrier frame, the upper part of said conveyor having a horizontal run and an inclined run leading upwardly therefrom, series of tines pivotally mounted to spaced transverse slats in said carrier, said tines normally resting rearwardly on the conveyor, means for automatically raising said tines to substantially perpendicular position while traveling up said inclined run of the conveyor, a floor and a wall on the carrier frame for holding said tines up against the underside of the

conveyor during the return run thereof, said floor and wall having their adjacent ends spaced apart from each other.

4. In a shock loading machine, a suitably mounted carrier frame having a horizontal portion and an inclined portion leading upwardly therefrom, an endless conveyor mounted on rollers rotatably mounted in said frame, means for rotating said rollers, said carrier frame having grooves therein, transverse slats in said conveyor, the ends of said slats being adapted to travel in said grooves, rods oscillatably mounted in certain of said slats, integral tines extending perpendicularly from said rods through slots in the respective slats, said tines resting normally rearwardly on the conveyor, and means for raising said slats to substantially perpendicular position while traveling up the inclined run of the conveyor.

5. In a shock loading machine, a suitably mounted carrier frame having a horizontal portion and an inclined portion leading upwardly therefrom, an endless conveyor mounted on rollers rotatably mounted in said frame, means for rotating said rollers, said carrier frame having grooves therein, transverse slats in said conveyor, the ends of said slats being adapted to travel in said grooves, rods oscillatably mounted in certain of said slats, integral tines extending perpendicularly from said rods through slots in the respective slats and normally inclined rearwardly against the conveyor

slots in the respective slats, fixed angular fingers on the ends of said rods, and actuating strips secured to the inner sides of the inclined portion of the carrier frame, said strips being adapted to actuate said fingers during their upward run with the conveyor.

6. In a shock loading machine, a suitably mounted carrier frame having a horizontal portion and an inclined portion leading upwardly therefrom, an endless conveyor mounted on rollers rotatably mounted in said frame, means for rotating said rollers, said carrier frame having grooves therein, transverse slats in said conveyor, the ends of said slats being adapted to travel in said grooves, rods oscillatably mounted in certain of said slats, integral tines extending perpendicularly from said rods through slots in the respective slats and normally inclined rearwardly against the conveyor when idle, fixed angular fingers on the ends of said rods, the ends of said rollers being spaced from the carrier frame to permit the passage of said fingers therebetween, and actuating strips secured to the inner sides of the inclined portion of the carrier frame, said strips being adapted to actuate said fingers during their upward run with the conveyor.

In testimony whereof I affix my signature.

BERT A. JOHNSON
